Des. 1466

William A. Greene, of Albany, N. Y.
Whole No. 1466. Letters Patent No. 101, dated Aug. 13, 1861.

The schedule referred to in these Letters Patent and making part of the same.

To all whom it may concern:

Be it known that I, William A. Greene, of the City and County of Albany, in the state of New York, have invented or produced, a certain new and ornamental design, for a Laundry and Heating Stove, and I do hereby declare that the following is a full, clear and exact description of the same, reference being had to the annexed drawings, and to the letters of reference marked thereon, forming part of this specification, in which—

Fig. 1. is a side elevation, and

Fig. 2. is a half plan view of the top.

The shading of Fig. 1. and the half plan view, Fig. 2, are intended to show that the stove is of a circular or round form.

The description is as follows. A and B, is the base of the stove, the top edge of A, finishing with a half round bead, as shown at a; the top edge of B, finishing with a quarter round bead b. C is the fire pot resting upon the base, the joining edges of the fire pot, and heating plate D, form a half round bead c. E, is the cap piece, F, the pipe collar. G, is the top plate, its outer edge or border, finishing with a quarter round bead d. and H, is the foot or leg of the stove.

Having described my design for a laundry and heating stove, what I claim as new therein, and desire to secure by Letters Patent, is.

I claim the design, or form, as herein described, and shown in the annexed drawings, the same constituting the external form or design for a laundry or heating stove.
